UNITED STATES PATENT OFFICE.

MOSES MOSLER, OF CINCINNATI, AND CARL BARTELS, OF HAMILTON, OHIO,
ASSIGNORS TO THE MOSLER SAFE COMPANY, OF NEW YORK, N. Y.

VAULT-VESTIBULE.

1,349,138.

Specification of Letters Patent. Patented Aug. 10, 1920.

Application filed September 22, 1919. Serial No. 325,577.

To all whom it may concern:

Be it known that we, MOSES MOSLER and CARL BARTELS, citizens of the United States, residing at Cincinnati, Hamilton county, 5 Ohio, and Hamilton, Butler county, Ohio, respectively, have invented certain new and useful Improvements in Vault-Vestibules, of which the following is a specification.

This invention, pertaining to the vestibules of vaults, relates to a construction of steel castings, and the improvements will be readily understood from the following description taken in connection with the accompanying drawings in which:

15. Figure 1 is a front elevation of a square door vault vestibule embodying our present improvements, portions appearing in vertical sections in the plane of line *a* of Fig. 2:

20. Fig. 2 a horizontal section through a portion of the vestibule wall and door in the plane of line *b* of Fig. 1, the door appearing as not being entirely closed: and

25. Fig. 3 a rear elevation of the juncture between one of the side walls of the vestibule and the contiguous vault wall.

A diversity of scales is employed in the drawings.

In the drawings:—

30. 1, indicates the wall of the vestibule:

2, the door thereof, the door being illustrated in the exemplification, as square:

3, the front wall of the vault, which is joined by the vestibule at the doorway:

4, the stepped jamb of the doorway:

35. 5, one section of the vestibule wall, the same being a steel casting with its rear exterior joining the wall 3 of the vault:

40. 6, a typical means for uniting the section 5 to the vault wall, the same consisting of dovetailed keeper blocks engaging dovetails on the contiguous portions of the vault wall and the vestibule wall:

45. 7, the second section of the vestibule wall, the same seating against the front of the section 5:

8, the third section of the vestibule wall the same seating against the front of the section 7:

50. 9, the fronts of the several sections 5, 7 and 8:

9', dovetailed grooves formed in the fronts of the sections 5 and 7:

55. 10, dovetails formed at the rear of the sections 7 and 8 and fitting loosely in the dovetails 9':

11, filling strips driven tightly between the side engaging surfaces of the dovetails uniting the several sections:

12, the front section of the door:

13, the next inner section of the door: 60

14, the inner section of the door:

15, the bolts of the door: and 16, filling strips driven into the spaces between the succeeding door sections, these door sections being dovetailed to each other in a manner 65 similar to that in which the vestibule sections join each other; and 17, packing of yielding material at the face of one of the steps.

While the vestibule and the door may be 70 formed each of any desired number of sections, the illustration assumes three sections in each, the door-jamb, and the door-margin being formed with three steps. Each vestibule section is formed of an integral steel 75 casting, and the rear section 5 is to be joined, in any desired manner, to the front wall 3 of the vestibule, as for instance, by means of the keeper-block 6. The contiguous sections of the vestibule wall engage each other 80 by loose dovetailing, the looseness being later taken up by the filling strips 11 which are tightly and permanently driven in place. The steps 4 of the door-jamb are beveled, and the beveling of these jamb- 85 portions serves in providing portions of the dovetailed junctures between neighboring sections.

The door is formed of sections dovetailed together in a manner similar to that employed in joining the vestibule sections, the tapers of the steps on the margin of the door forming elements in the union of the door sections. By this system of construction, any desired thickness of door and door-jamb 90 may be secured while maintaining comparatively thin individual wall sections.

In assembling the vestibule the casting constituting a given section, say the section 5, is first taken in hand, this section forming 100 the top, bottom and both sides of one step of the doorway. The next section 7, similarly constructed, is then to be placed in its dovetail connection with the section 5 and the filling strips are to be tightly driven, 105 thus securing the two sections of the doorway firmly together. The next section is 8, to be similarly joined to the preceding two sections. A similar method of assembling is to be employed in connection with the door, 110

each section of which embodies the top, bottom and two sides of one step of the door.

The door, which in the exemplification is illustrated as being square, may be round or of other shape, and the walls and door may be formed of steel castings, preferably manganese steel, and the filling strips will preferably be of manganese steel if manganese steel be the material employed for the general construction. If it be desired that a yielding packing be employed it may be provided at the shoulder of any one of the steps by employing, at such steps, filling strips shallower than the depth of the groove in which they fit, the front of the groove being filled with the packing which would project a slight distance beyond the face of the step.

By means of the described system of construction not only may the doorway and door be built up to any desired depth, but it is our preference that hollow manganese steel castings be employed in building up the structure and in the drawing we illustrate the sections of door and wall as being hollow. It is preferable that the hollows of the sections be strengthened by means of girts cast across the cavities, as shown. By thus employing hollow sections formed of manganese steel castings, the walls of the cavities may be comparatively thin, thus permitting of the satisfactory heat treatment of the manganese steel. In case the sections be formed of hollow castings the cavities in them may, if desired, be filled with any suitable fireproofing or other material.

We claim:

1. A vault vestibule comprising, a vestibule section having a front provided with a dovetail and with an inner door-step, a second similar section having a dovetailed juncture with the first-mentioned section, tightly fitted filling strips engaging the dovetailed elements of the two sections, an inner door section, a second similar door section having a dovetailed connection with the front of the first-mentioned door section, and filling strips tightly fitting permanently between the engaging dovetailed elements of the two door sections, combined substantially as set forth.

2. A vault vestibule comprising, a vestibule section, a dovetail formed in the front of said vestibule section, a second similar vestibule section having at its rear a dovetail adapted to engage the dovetailed front of the first-mentioned section, and filler strips fitted permanently between the engaging dovetail elements of the two sections, combined substantially as set forth.

3. A vault vestibule comprising, an inner door section having a margin exteriorly dovetailed at its front, a second similar door section having dovetailed portions at its

rear adapted to engage over the dovetailed margin of the first door section, and filler strips disposed between the adjacent dovetail elements of the two door sections, combined substantially as set forth.

4. A vault vestibule comprising, a vestibule section provided with an inner door-jamb and provided with the exterior members of a dovetail at its rear, a second similar section provided with an inner door-jamb in stepped relationship with the door-jamb of the first section and provided on its front with dovetailed members adapted to engage within the dovetailed members of the first mentioned section, tightly fitted filling strips engaging the dovetail elements of the two sections, and a door having a stepped margin to engage the jamb portions of the vestibule sections, combined substantially as set forth.

5. A vault vestibule comprising, a vestibule section having a front provided with a dovetail and with an inner door-jamb, a second similar section having a dovetailed juncture with the first-mentioned section, tightly fitted filling strips engaging the dovetail elements of the two sections at the door-jamb and having a depth less than the groove in which they fit, and yielding packing disposed in the front of the groove in which said filling strips are fitted, combined substantially as set forth.

6. A vault vestibule comprising, a hollow vestibule section open at its back and having a solid front provided with a dovetail and with an inner door-step, a second similar section having a dovetailed juncture with the first-mentioned section, tightly fitted filling strips engaging the dovetail elements uniting the two sections, and a door having a stepped periphery engaging within the vestibule sections, combined substantially as set forth.

7. A vault vestibule comprising, a vestibule having a stepped door-jamb, an inner door section open at its back and closed at its front and having a margin adapted to fit in the smaller step of the door-jamb of the vestibule, a second similar door-section having a dovetail engagement with the front of the first door section and having a periphery fitting the larger step of the door-jamb of the vestibule, and tightly fitted filling strips engaging the dovetail elements of the two door sections, combined substantially as set forth.
